United States Patent Office

Des. 204,384
Patented Apr. 12, 1966

204,384

RECORD CARD VERIFYING MACHINE OR SIMILAR ARTICLE

William C. Reboulet, Dayton, Ohio, assignor to The National Cash Register Company, Dayton, Ohio, a corporation of Maryland

Filed May 5, 1965, Ser. No. 85,109

Term of patent 14 years

(Cl. D26—5)

FIG. 1

FIG. 2

FIG. 1 is a front perspective view of a record card verifying machine or similar article, showing my new design; and

FIG. 2 is a rear perspective view thereof.

The dominant features of my design reside in the full-line portions of the drawings.

I claim:

The ornamental design for a record card verifying machine or similar article, as shown and described.
